(57) **CLAIM**

The ornamental design for a hemp plastic container as shown and described.

DESCRIPTION

FIG. 1 is a perspective view of a first embodiment of a hemp plastic container;

FIG. 2 is a front view of the first embodiment;

FIG. 3 is a back view of the first embodiment;

FIG. 4 is a right side of the first embodiment;

FIG. 5 is a left side view of the first embodiment;

FIG. 6 is a top view of the first embodiment;

FIG. 7 is a bottom view of the first embodiment;

FIG. 8 is a perspective view of a second embodiment of the hemp plastic container;

FIG. 9 is a front view of the second embodiment;

FIG. 10 is a back view of the second embodiment;

FIG. 11 is a right side of the second embodiment;

FIG. 12 is a left side view of the second embodiment;

FIG. 13 is a top view of the second embodiment; and,

FIG. 14 is a bottom view of the second embodiment.

The broken lines in the drawings depict portions of the hemp plastic container that form no part of the claimed design.
